Avia, Inc., Dayton, Ohio, a corporation of Illi-
nois

Application July 13, 1940, Serial No. 93,600

Term of patent 14 years

To all whom it may concern:

Be it known that I, William P. Lear, a citizen
of the United States, residing at Dayton, in the
county of Montgomery and the State of Ohio,
have invented a certain new, original, and orna-
mental Design for a Radio Control Panel Unit,
of which the following is a specification, reference
being had to the accompanying drawing, forming
part thereof.

Fig. 1 is a front elevational view of a radio
control panel unit showing my new design; and
Fig. 2 is a top plan view thereof.

I claim:

The ornamental design for a radio control
panel unit, substantially as shown.

WILLIAM P. LEAR.
